UNITED STATES PATENT OFFICE.

DREW D. ROBERTS, OF PERRY, FLORIDA.

STUMP-EXTRACTOR.

1,372,551.

Specification of Letters Patent. Patented Mar. 22, 1921.

Application filed May 13, 1920. Serial No. 381,115.

To all whom it may concern:

Be it known that I, DREW D. ROBERTS, a citizen of the United States, residing at Perry, in the county of Taylor and State of Florida, have invented certain new and useful Improvements in Stump-Extractors, of which the following is a specification.

This invention relates to machines for extracting stumps, and pertains especially to 10 mechanism for operating an elevating screw or worm connected with a stump.

The object of the invention is to provide a supporting frame, adapted to be anchored around a stump, with a plurality of gears or 15 pinions meshing with an annular gear of a hollow cone-shaped head through which a screw shaft works for pulling stumps.

A further object of the invention is to provide a hollow cone having a screw head for 20 operating a screw shaft, and having an annular gear meshing with a plurality of pinions, one of which is driven for revolving the cone and the other pinions, in a stump pulling operation.

25 Various other objects, advantages and improved results are attainable in the manufacture and practical application of the invention.

In the accompanying drawings forming 30 part of this application:—

Figure 1 is an elevation showing the application of the invention as in a stump pulling operation.

Fig. 2 is a top view with the cone partly 35 broken away.

Fig. 3 is a vertical sectional view of the cone head showing the screw or lifting shaft in elevation.

Fig. 4 is a bottom view of the cone head.

40 Fig. 5 is a perspective view of a modification.

The same reference characters denote the same parts throughout the several views of the drawings.

45 In carrying out my invention, I employ a supporting frame comprising uprights 1 braced and joined together by frame members 2 so as to leave a central opening 3, and the lower end of the uprights 1 are connected 50 by braces 4, affording a substantial rigid frame with said uprights depending from each corner of said frame. Each of the uprights 1 has joined therewith an adjustable ground leg 5 which may be adjusted to span 55 stumps or other articles to be lifted according to the size thereof.

Upon each corner of the said supporting frame is secured journal bearings 6 for pinions 7 which have their axis line of rotation central of the frame opening 3, and one of the pinions is operated by a pulley 8 and belt 9 driven by any convenient and suitable driving power.

A hollow cone-shaped head 10 is revolvably mounted above the pinions 7 by means of a bearing ring 11 connected with the supporting frame by bars 12, and the bottom of said head is provided with an annular flange 12^a, having an annular gear 13 which meshes with the pinions. The top of the cone head 70 has a screw socket or collar 14 through which a lifting screw shaft 15 is worked vertically by the revolution of the cone head in a stump extracting operation. The lower end of the shaft 15 has swiveled thereto suitable grapples 16 for grasping a stump, and the ground end of the legs 5 has base pieces 17 or other suitable means for anchoring them.

Attention is specially directed to the advantages of the cone-shaped head 10, in that its hollow cone-shaped construction with unusual length or height affords strengthening and bracing means between the supporting structure and the apex of the cone and between the latter and the screw shaft, and also affords increased length of hoist or vertical movement of said shaft without adjusting the supporting structure, while the latter may be adjusted vertically with respect to a stump without detaching or separately adjusting the cone-head.

Obviously the shaft is raised by revolving the cone head, and said shaft is lowered into position for stump pulling by merely reversing the movement of the cone head. The grapple connection is such as to permit of having the grapple hook to stump roots, and to a cable or chain secured to a stump for purposes of extraction.

Referring to the modification shown in Fig. 5 of the drawings, the head of the cone 95 has a socket 19 for holding a nut 20 as the shaft 21 screws therethrough in a pulling or lifting operation, permitting the shaft and the nut to be raised and lowered preparatory to the said operation, without operating the cone.

I do not wish to confine my invention as to material, size, shape, capacity and application, but reserve the right to make such changes and variations therein and in the

parts thereof, and in the manufacture and practical application thereof as may come within the scope of the appended claim.

Having thus described my invention what 5 I claim as new and desire to secure by Letters Patent is:—

In a stump extractor, a hollow cone-shaped head the apex of which has formed therein a screw-threaded collar, the flaring open end 10 of said cone having an annular bracing flange member provided upon its under side with an annular gear, a supporting structure for said cone, an annular bearing ring fitting the said flange and attached to the

top of said structure for permitting rotary 15 movement of the cone, a plurality of pinions journaled on the top of said structure and meshing with said annular gear, driven means for operating the pinions, and a screw shaft extending through the cone-head 20 and screwing through the said collar.

In witness whereof I hereunto set my hand in the presence of two witnesses.

DREW D. ROBERTS.
